UNITED STATES PATENT OFFICE.

WALTER A. SAGUE, OF BUFFALO, NEW YORK.

BASE FOR POSTS.

Application filed July 14, 1928. Serial No. 292,887.

This invention relates to fence posts and similar structures which are anchored in concrete blocks or bases and more particularly to the combination with the post and anchor-
5 age block of a conical cap fitted on the post and over the block.

When a post is anchored in concrete, a small crevice always remains between the post and the concrete regardless of the care taken
10 to avoid it. Inasmuch as this crevice collects moisture and thereby causes the post to rot or rust, the practice has been to slope the upper surface of the base so as to drain the moisture away from the post and thus reduce
15 the quantity collected in the crevice to a minimum. The sloping of the upper surface has been accomplished, heretofore, by hand troweling without the use of a troweling guide. As a result, this surface is wavy
20 and uneven and does not present a finished workmanlike appearance unless skilled labor is used. Furthermore, the bases of successive posts are not uniform, even with the use of skilled labor. These effects are particularly
25 objectionable in ornamental fences because of the resulting unsightly appearance of the fence and the expense required to avoid them under present practice.

The main object of this invention is to
30 provide a conical cap which may be set in place in such manner as to reduce the crevice between the base and post and which, when properly positioned, facilitates the sloping of the base whereby with the use of unskilled
35 labor, uniformity in slope of each base and of successive bases may be obtained.

The invention consists in a structural combination in which a cap is fitted upon a post anchored in a block of concrete and is pressed
40 against the concrete while soft in order to compact it against the post and force it into full engagement with the cap, the cap being of such size that it covers only a portion of the upper surface of the base whereby the surface of the cap is available as a troweling guide for the remaining surface of the base.

The invention is illustrated in the accompanying drawings, wherein:—

Figure 1 is a side elevation of a fence post construction utilizing the cap and shown in connection with a trowel.

Figure 2 is a central vertical section of the construction as a whole.

Figure 3 is a plan view with the post in section.

The conical cap 1 is composed of any suitable material, as metal, and truncated to an extent sufficient to insure a close fit upon the post 2. The slope of the cap is preferably, but not necessarily, made the same as the slope 60 of the base, inasmuch as a trowel may be readily obtained to conform to different degrees of slope between the cap and the remaining surface of the base.

In use, the cap 1 is fitted upon a post 2 which is properly anchored in a soft concrete base 3, and forced into contact with the coincident surface of the base. By tamping or otherwise positively forcing the cap upon the base, the concrete is compacted 70 against the post and at the same time forced into full engagement with the cap throughout its area. Preferably the cap is forced against the base until the concrete begins to exude through the crevice between the cap 75 and the post, the purpose being to fill and seal this crevice and thereby further insure against the access of moisture.

With the cap positioned in this manner, a trowel 4 of suitable form is utilized, this trowel being initially aligned by the cap and drawn around the post in engagement with the cap and the remaining surface of the base to shape such surface to its final or finished form, the cap having a counter-
80 sunk relation to the concrete.

The retention of the cap 1 upon the base 3 may be insured by forming the cap with inturned lugs 5 which extend into the base at an angle to the vertical. Where the lugs 90 5 are utilized, the concrete is preferably made to fill the holes created in the cap.

From the foregoing it is apparent that the cap when positioned in the manner described reduces the crevice between the base and post, seals the joint line of the cap and the post and at the same time effects a tighter joint and provides an easy and quick means of securing an even slope and unvarying surface throughout each base together with uniformity in slope of successive bases without the necessity of skilled labor or material expense otherwise.

Having fully described my invention, I claim:

1. The combination with a post having one end embedded in a block of soft concrete of a truncated conical cap adapted to encircle the post and engage a portion of the upper surface of the block, said cap providing a 110

guiding surface which facilitates the uniform shaping of the remaining upper surface of the block.

2. The combination with a post having one end embedded in a block of soft concrete of a truncated conical cap fitted upon the post and pressed into full engagement throughout its area with the base to compact the con-

crete around the post, said cap being of a size such that it covers only a portion of the base whereby it is available as a troweling guide for the remaining surface of the base. ¹⁰

In testimony whereof I hereby affix my signature.

WALTER A. SAGUE.
